UNITED STATES PATENT OFFICE.

EDWIN N. PREBLE, OF BEVERLY, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

STAMPING-MACHINE.

1,269,642.

Specification of Letters Patent. Patented June 18, 1918.

Application filed December 8, 1918. Serial No. 805,307.

To all whom it may concern:

Be it known that I, EDWIN N. PREBLE, a citizen of the United States, residing at Beverly, in the county of Essex and State 5 of Massachusetts, have invented certain Improvements in Stamping-Machines, of which the following description, in connection with the accompanying drawings, is a specification, like reference characters on the drawings indicating like parts in the several figures.

This invention relates to machines for stamping or branding with heated dies and is herein shown as embodied in a machine 15 for stamping the soles of boots and shoes.

For this class of work it is customary to employ a stamping machine having a movable die holder in which are held a number 20 of dies adapted for impressing upon the bottoms of boots and shoes monograms, trade-marks, price-marks or other symbols or designs. By the use of such a machine several different symbols may be impressed in a short space of time on the same shoe 25 sole, the die carrier being movable to bring the different dies into stamping position as required. One object of the invention is to provide improved heating means for a machine of this type.

30 It is desirable that the heating means be of such character that its effect will be localized and only such portions of the machine heated as is required, for otherwise the operation of the moving parts of the machine may be hindered by the resulting expansion. It is also desirable that the heating means be so 35 designed that all the dies in the die carrier will be maintained at substantially equal temperature so that no time need be lost in changing from one die to another. The heating device herein disclosed comprises one means by which these desirable results may be secured. To that end an important 40 feature of the invention consists in arranging the die carrier for movement upon a hollow or recessed spindle in which is disposed electrical heating resistance.

Another important feature of the invention 45 consists in the provision of heated holding means adapted to retain in convenient position those dies which are not at the time being used in the turret. By the use of such a device these dies may be kept heated somewhat so that when they are inserted in the

die carrier less time is required in bringing 55 them to the stamping or branding temperature than would be required in the case of cold dies.

These and other features of the invention, 60 some relating to the general construction of the machine and others to the arrangement of the electrical connections, will be best understood and appreciated from the following description of a preferred embodiment 65 thereof selected for purposes of illustration and shown in the accompanying drawings, in which,

Figure 1 is a view in perspective of portions of a stamping machine embodying my 70 invention, and

Fig. 2 is a sectional view of the die carrying head.

For purposes of illustration the invention is shown as embodied in a stamping machine 75 similar to that disclosed in United States Letters Patent No. 1,028,567, granted June 4, 1912, on an application of Gordon and Topham but it should be understood that the invention is in no sense limited to stamping machines of this or any particular type. 80

The machine frame 2 is provided with an overhanging arm in which is formed a vertical guideway for a plunger 4 which is arranged to reciprocate toward and from a horn 6 supported by the lower part of the 85 machine frame. The plunger 4 is reciprocated to effect the stamping operation by a lever 8 which may be oscillated by a cam or other suitable mechanism not shown. The plunger 4 is forked at its lower end and 90 carries a transverse bolt 10 which acts as a spindle for the die carrier or turret 12. The turret 12 has a plurality of radially disposed sockets for the stamping dies 14 and is arranged to turn between the forks of the 95 plunger 4 and upon the spindle 10 in order to bring the desired die into stamping position. A locking pin or detent, not shown, may be provided for holding the turret against rotation with one or another stamping die in proper position.

The spindle 10 is made hollow to receive 100 a pair of coils 16 of electric heating resistance placed end to end. These coils are thus located at equal distances from each die in the turret so that all the dies will be maintained at substantially the same temperature. The heating means, moreover, is un-

affected by the adjusting movement of the turret upon the spindle as the latter is not turned with the turret.

The spindle 10 is threaded at its outer ends and extends through the forks of the plunger 4 being provided at each end with a nut 18 having a tubular projection or wire guide 20 on its outer side. Connecting wires 22 for the heating coils 16 pass outwardly 10 through the ends of the spindle and through the tubular wire guides 20. Within these guides 20 are disposed a number of loose perforated disks 24 of insulating material through which the wires extend. One purpose of this construction is to insure that the insulation of the connecting wires 22 shall not be subjected to wear or the wires themselves broken as the plunger 4 carrying the heating coils moves up and down in the 20 stationary frame 2.

The connecting wires 22 pass upwardly on each side of the machine from the wire guides 20 through tubular retainers 26 secured to the frame 2 and then to the poles of 25 a switch 28 mounted on a switch-board 30 secured to the frame. The switch-board 30 also carries a double pole switch 32, by which the electric current may be entirely cut off from the machine when desired, and 30 a small lamp 34 so connected as to be illuminated when current is being consumed.

The guideway in the frame 2 for the plunger 4 is closed at its forward side by a cover plate 40 having on its outer face a 35 number of projecting bosses 42 each provided with an oblique socket 44 for the reception of a die. The sockets in the plate 40 afford convenient retaining means for the dies not actually in use and, as this plate is 40 somewhat heated through the heated turret 12 and plunger 4 from the coils 16, these dies are maintained at all times in a warm condition and will be quickly raised to the required temperature when inserted in the 45 turret.

It is believed that the operation of the machine will be apparent from the foregoing description but it may briefly be set forth as follows: The operator having first inserted in the turret those dies which are required for the work in hand throws in the switch and allows the turret and dies to become sufficiently heated for branding. The boot or shoe to be stamped is then 55 placed on the horn 6 and the machine set in operation. Thereupon the plunger 4 is moved downwardly and the heated die forced against the sole for an interval sufficient to brand the desired symbol into the 60 sole. The plunger 4 is then elevated and the turret may be turned to bring another die into stamping position, the work continuing in this manner until the required 65 symbols have been impressed when another shoe may be presented.

Having thus described my invention, I claim as new and desire to secure by Letters Patent of the United States:

1. In a stamping machine adapted to operate with interchangeable dies, a metallic plate with a plurality of projecting bosses, each boss having a die-receiving socket inclined with respect to the surface of the plate, and means for heating the plate. 75

2. A stamping machine having, in combination, a rotatable turret, a hollow spindle therefor, electric heating means disposed wholly within said spindle and having flexible conductors for the heating means extending from within the spindle out through the end of said spindle, and a threaded tubular extension rigid with the spindle end, said extension serving as a guide for the flexible conductor and aiding in the retention of the turret upon the spindle. 80

3. A stamping machine having, in combination, a reciprocating plunger forked at one end, a hollow spindle extending through the forks of the plunger and rigidly secured thereto, a die carrying turret rotatably mounted upon the spindle between the forks, electric heating means disposed in the bore of the hollow spindle and extending outwardly to the plane of the side surfaces of the plunger whereby both the turret and the forks of the plunger are heated, and a die carrier to which the heat of the forks is communicated. 85

4. A stamping machine having, in combination, a stationary frame, a forked plunger mounted for reciprocation in the frame and carrying a die holder, a transverse bolt for maintaining the die holder in the plunger, electric heating means disposed within the bolt, a tubular nut for securing the bolt to the plunger, connecting wires passing through said tubular nut to the heating means, and a wire retainer on the stationary frame. 100

5. A stamping machine having, in combination, a stationary frame, a reciprocating plunger mounted therein, carrying and being heated by electric heating means, and a carrier plate secured to the frame adjacent to the plunger where it will be heated from the heated plunger and having die holding sockets in its face. 110

6. A stamping machine having, in combination, a stationary frame having a guideway, a plunger mounted therein and carrying a turret with die sockets, a carrier plate with die sockets, and a heating device common to both the turret and the carrier plate, said turret and plate being so disposed that one is warmed by the other. 120

7. A stamping machine having, in combination, a stationary frame having a guideway and a cover plate with a series of projecting bosses on its face, each boss having 125

an obliquely disposed die socket therein, a die carrier mounted to reciprocate in the guideway, and means movable with the die carrier for heating both it and the cover plate.

5 8. In a stamping machine adapted to operate with interchangeable dies, a metallic plate with a plurality of bosses formed thereon, each boss having an inclined upper surface, a tapering body portion and a die-

receiving opening, and means for heating the plate.

In testimony whereof I have signed my name to this specification in the presence of two subscribing witnesses.
